United States Patent Office

Des. 217,858

Patented June 23, 1970

217,858

BARREL RESTAURANT BUILDING

Spero Mihilas, Belleville, Ill.
(1862 Lake Spier Drive, Winter Park, Fla. 32789)

Filed July 25, 1969, Ser. No. 18,413

Term of patent 3½ years

Int. Cl. D25—04

U.S. Cl. D13—1

FIG. 1 is a top plan view of a barrel restaurant building showing my new design;

FIG. 2 is a front elevational view thereof;

FIG. 3 is a rear elevational view thereof;

FIG. 4 is a left side elevational view thereof; and

FIG. 5 is a right side elevational view thereof.

I claim:

The ornamental design for a barrel restaurant building, substantially as shown.
